(57) **CLAIM**

We claim the ornamental design for a chip and light emitting diode panel housing, as shown and described.

DESCRIPTION

FIG. 1 is a perspective view of a chip and light emitting diode panel housing in accordance with the design;

FIG. 2 is a front view of the housing of FIG. 1;

FIG. 3 is a back view of the housing of FIG. 1;

FIG. 4 is a left view of the housing of FIG. 1;

FIG. 5 is a right view of the housing of FIG. 1;

FIG. 6 is a top view of the housing of FIG. 1; and,

FIG. 7 is a bottom view of the housing of FIG. 1.
